UNITED STATES PATENT OFFICE.

MARTIN SPALL, OF ALLIANCE, OHIO.

TOILET-PAPER HOLDER.

1,158,577.

Specification of Letters Patent. Patented Nov. 2, 1915.

Application filed May 5, 1915. Serial No. 25,922.

To all whom it may concern:

Be it known that I, MARTIN SPALL, a citizen of the United States, residing at Alliance, in the county of Stark and State of 5 Ohio, have invented a certain new and useful Improvement in Toilet-Paper Holders, of which the following is a specification.

The object of this invention more particularly is to provide means tending to deter the 10 inconsiderate and wasteful use or unlawful conversion of toilet paper, and the invention consists generally in an improved mechanism which compels the setting of an automatic latching mechanism which permits 15 after such setting and before a resetting of the mechanism of the removal of a limited portion only of the paper.

In the accompanying drawing illustrating 20 an embodiment of the invention, Figure 1 is a view in front elevation showing a toilet paper holder according to my invention. Fig. 2 is a view of the left hand end as shown in Fig. 1 with the cover for that end removed. Fig. 3 is a top plan view of the 25 mechanism case with parts in section. Fig. 4 is a detail on the line α — α Fig. 3 looking toward the front of the device.

In the views 5 designates a hood or case 30 provided with flanges 5^a having screw holes for fastening the same to a wall. The case is divided by a wall 16 into two compartments 6 and 7 the former to receive a roll 8 of toilet paper and the latter to receive the mechanism. Each of these compartments 35 has a removable cover for its outer end, each of said covers being adapted to be secured with a padlock or by any other suitable means. The compartment 6 is provided with a slot 6^a through which the paper is 40 drawn to remove it from the roll.

Rotarily mounted in the case is a hollow shaft or spindle 10. The roll of toilet paper 8 is secured to the hollow spindle 10 in the compartment 6 or at the right hand end of 45 the spindle by means of a pair of elastic pronged fingers 11, 11 extending from a perforated thimble 12, said fingers being connected by a bridging member 13. Connected with said bridging member 13 is a threaded 50 stem 14 provided with a thumb nut 15 abutting against the end of the thimble 12 so that by turning the nut in the proper direction the pronged fingers can be withdrawn from or permitted to engage the inner core 55 of the paper roll through appropriate open-

ings in the hollow spindle. But any approved means can be employed to lock the roll to the spindle to cause the unwinding of the paper to impart rotary motion to the spindle. The cover for the right hand end 60 of the case can have a supplemental portion 30 attached with it to inclose the end of the spindle and the nut 15 to prevent unauthorized manipulation thereof.

Secured to the left hand end of the hollow 65 spindle within the compartment 7 is an annular ring or projection 17 having a tooth or shoulder 18 in its periphery and a lug or stop on its side, said shoulder 18 and lug 19 being at nearly opposite points. The 70 spindle 10 is also provided with a radially extending finger 20. Pivoted on the wall 16 is a gravity pawl 21, the free end of which normally rests in the path of rotation of the tooth or shoulder 18, so as to prevent the 75 turning of the spindle in a direction to permit the withdrawal of the free end of the paper roll. Slidingly mounted in the case and in a projecting plate 16^a above the pawl 21 is a key rod 22 to which rod the pawl is 80 connected by a flexible member 23 passing over a small pulley 24. Arranged in line with the inner end of the rod 22 is the upper 85 end of a lever 25 fulcrumed on the wall 16, the lower end of said lever constituting a pawl to be projected into the path of the lug 19 and prevent the rotation of the paper roll 90 spindle, should the rod be unduly held inward. The pawl lever 25 is normally held withdrawn from the path of the lug 19 by 95 means of a coil spring 26 attached to it and the case. 29 is an adjustable stop to limit the movement in one direction of the lever 25.

The key rod 22 is made with a notch 22^a and mounted on a projection in the compartment 6 is a latch lever 27 provided with a spring 28 tending to press the latch lever toward the key rod so that when the key rod is pressed inward the latch lever shall automatically slip into said notch and lock the 100 same from movement. The lower arm 27^a of the latch lever 27 is bent to lie in the path of the radially extending finger 20.

The operation is briefly this: When it is 105 desired to remove a portion of the paper from the roll the key rod 22 is pushed in until caught by the latch lever 27. This operation lifts the gravity pawl 21 from in front of the tooth 18 so that the paper roll spindle 10 can be turned by drawing out the 110

free end of the paper strip but only a single rotation can be made after a single operation of the key rod because when the spindle 10 is partly turned the radial finger 20 actuates the latch lever 27 to release the key rod 22 which is then restored to normal position by the coil spring 26. Upon the completion of the rotation of the spindle and paper roll the gravity pawl 21 falls in front of the tooth 18. The pressing in of the key rod 22 also presses rearward the upper arm of the lever 25 and projects the toe of the lower end of that lever into the path of the lug 19 but because in proper operation the push key 22 is automatically released by the operation of the radial finger 20 on the latch lever 27, the said toe of the lever 25 is then retracted and does not operate to prevent the rotation of the paper. If, however, it be attempted by the user to withdraw from the roll more than one layer of paper by holding in the push key 22 the attempt will be frustrated by the abutment of the lug 19 against the said toe of the lever 25 thereby preventing the rotation of the paper roll spindle. Of course, several pieces or one strip made up of several pullings can be taken from the roll but this involves several operations of the push key 22 which operations are accompanied by more or less noise and indeed can operate a specially provided signal if

desired, and as will readily occur to those skilled in mechanics.

The form of the parts can be varied without departing from the gist of the invention as claimed.

What I claim is:

1. A toilet paper holder comprising, in combination, a case, a paper roll spindle, means for securing a paper roll thereto to rotate therewith, means for latching the spindle from rotation, a key for releasing the said latching means, means for latching said key when the same has been actuated, and means carried by the paper roll spindle for automatically releasing the key when the paper roll spindle is turned. 45

2. A toilet paper holder comprising, in combination, a case, a paper roll spindle, means for securing a paper roll thereto to rotate therewith, means for latching the spindle from rotation, a key for releasing the said latching means, means for latching said key when the same has been actuated, means carried by the paper roll spindle for automatically releasing the key when the paper roll spindle is turned, and means for preventing the complete rotation of the paper roll spindle until after the key is released. 50 55

MARTIN SPALL.
